UNITED STATES PATENT OFFICE

WALLACE F. WOLFE, OF SCHENECTADY, NEW YORK.

PIPE-VISE CLAMP.

1,225,301.

Specification of Letters Patent.

Patented May 8, 1917.

Application filed March 29, 1915; Serial No. 17,663. Renewed March 15, 1917. Serial No. 155,092.

To all whom it may concern:

Be it known that I, WALLACE F. WOLFE, a citizen of the United States, residing at Schenectady, county of Schenectady, and 5 State of New York, have invented certain new and useful Improvements in Pipe-Vise Clamps, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a horizontal, cross-section of an upright circular post, 20 showing a top plan view of my improved pipe-vise-clamp applied to the post.

Fig. 2 is a view in side elevation of the upright post with the clamp applied thereto, showing a pipe-vise supported by the clamp.

Fig. 3 is a plan view of the inner side of 25 the smaller clamp-plate.

Fig. 4 is a central, longitudinal section of the same taken on the broken line 4—4 in Fig. 3.

Fig. 5 is a horizontal, cross-section of an 30 oblong rectangular post, showing a plan view, partly in section, of a modified form of clamp embodying my invention.

Fig. 6 is a top plan view of the base-plate 35 of the clamp partly broken away.

Fig. 7 is a vertical, longitudinal section of the same taken on the broken line 7—7 in Fig. 6.

Fig. 8 is a plan view of an extension bar 40 for the base-plate of the clamp shown in Fig. 5.

Fig. 9 is a plan view of the complementary clamp-member shown in Fig. 5.

The principal object of the invention is 45 to provide a clamping-mechanism whereby pipe-vises of various kinds can be readily attached to, and detached from, posts of different sizes and form.

Referring to Figs. 1, 2, 3, 4, 6 and 7 of 50 the drawings, 1 is the base-plate of the clamp provided with a plurality of slots, 2, adapted to adjustably receive screw-bolts, 3, whereby the base, 4, of a pipe-vise, 5, can be detachably mounted upon the base-plate, 1, of the 55 clamping-mechanism.

Pipe-vises of different kinds are ordinarily provided with bolt-apertures in the base of the vise, and by providing a plurality or series of elongated slots, 2, in the clamp-base-plate, 1, the base of the vise can be so placed upon the outer side of the clamp-base-plate, 1, that bolts inserted through the apertures in the base of the vise can be passed through certain of the slots, 2, whereby the pipe-vise can be detachably mounted upon the outer side of the clamp-base-plate, as shown in the drawings.

Along the opposite edges of the clamp-base-plate, 1, on its inner side are a pair of bearing blocks or flanges, 6, each having a substantially flat face, 7, in which are formed at about the middle of the flange or block, a series of stepped seats, 8, adapted to receive cylindrical posts of different diameters.

The complementary clamping-member, 9, has on its inner side a flat face, 10, in the middle of which are formed stepped seats, 11, similar to the stepped seats, 8.

An eye-bolt, 12, is pivoted at 13 between 80 a pair of ears, 14, on one end of the clamp-base-plate, 1, the shank of said bolt being adapted to pass through an aperture, 15, in the complementary clamping-member, 9.

The opposite end of the clamp-base-plate, 85 1, is provided with an open slot, 16, and the plate is undercut or recessed on the outer side along the edges of said slot to receive the head, 17, of a screw-bolt, 18, the shank of which is readily inserted within, and removed from, said open slot.

The shank of the screw-bolt, 18, is adapted to pass through an aperture, 19, in the complementary clamping-member, 9; and by means of nuts, 20, on the projecting ends 95 of the bolts, 18, the clamping-members can be drawn toward each other to tightly embrace between them a post, as the post, 21, and thus serve to support the pipe-vise in a convenient position for use.

The post, 21, is shown as a circular or cylindrical post occupying the stepped seats, 8 and 11 in the respective clamping-members.

In Fig. 1 I have indicated by broken lines, 21^a, a rectangular post to which the clamp could be applied in substantially the manner above described, except that the rectangular post would be embraced between the flat surfaces, 7 and 10, on the respective 105 110

clamping-members instead of by the stepped seats, 8 and 11.

The clamp can be readily released by loosening one of the nuts, 20, sufficiently to permit the headed end of the bolt, 18, to be swung out from the open slot, 16.

When the pipe-vise is to be mounted upon a flat-sided post of a width greater than the distance between the bolts, 12 and 18, I substitute for the clamping-member 9, a longer flat clamping-member, 22, provided at one end with an aperture, 23, corresponding to the aperture, 15, to receive the bolt, 12, and at the other end with a series of open slots, 15 24, into a selected one of which, the bolt, 18, can be laterally inserted; and I removably mount upon the clamp-base-plate, 1, an extension clamp-bar, 25, provided with a series of bolt-holes, 26, for the bolt, 18, corresponding in position with the respective open slots, 24, in the clamp-member, 22.

The extension bar, 25, has at one end a tongue, 27, adapted to be inserted between the ears, 14, and between the pivoted end of 25 the eye-bolt, 12, and the inner side of the clamp-base-plate.

Near its other end the extension clamp-bar, 25, has formed thereupon a hook, 28, adapted to occupy the undercut or recess in 30 the clamp-base-plate adjacent to the open slot, 16.

For convenience in casting the extension bar, 25, the bar may be provided with an aperture, 29, beneath a part of which the 35 hook, 28, extends.

In applying the extension bar, 25, to the base-clamp-plate, the tongue, 27, is slid into its seat between the ears, 14, at the same time that the hook, 28, is slid into the undercut or recess adjacent to the open slot, 16, and when thus seated the pull of the bolt, 18, upon the extension bar, 25, is transmitted to the clamp-base-plate.

The last described construction is shown 45 in Fig. 5 clamped upon an oblong rectangular post, 30.

Instead of using the form of complementary clamping-member, 22, the clamping-member, 9, may be made of sufficient length 50 and provided with additional bolt-openings, 31, to adapt it for use with the extension bar, 25, as well as with the clamp-base-plate, 1, and in Fig. 4 I have shown the clamping-member, 9, partly broken away.

What I claim as new and desire to secure 55 by Letters Patent is—

1. A pipe-vise-clamp, having in combination, a clamp-base-plate provided with a plurality of bolt apertures for interchangeable connection with the bases of different pipe-vises and having along its opposite sides bearing-flanges formed with stepped seats and with extended flat bearing-surfaces on opposite sides of said stepped seats; a clamp-member complementary to said clamp-base-plate having stepped seats and on either side thereof an extended flat bearing-surface; and screw-mechanism for drawing together said clamp-base-plate and said complementary clamping member independently of the base of the pipe-vise. 70

2. In a pipe-vise-clamp, and in combination, a clamp-base-plate provided with bolt-holes for connection with the base of a pipe-vise; an extension bar detachably secured 75 to said clamp-base-plate, both said clamp-base-plate and said extension bar being adapted to receive screw-mechanism; a clamping-bar complementary to said clamp-base-plate; and screw-connections between 80 said complementary clamping-bar; and either said clamp-base-plate or said extension-bar interchangeably.

3. In a pipe-vise-clamp, and in combination, a clamp-base-plate provided with bolt-holes for connection with the base of a pipe 85 vise and with an opening for a clamping-bolt; of an extension-bar detachably secured to said plate, said bar having a hook embracing a portion of the plate at one end 90 and being provided with an opening for a clamping-bolt; a clamping-member complementary to said clamp-base-plate provided with bolt-apertures; a screw-bolt connected with one end of said complementary clamping- 95 member and adapted to interchangeably occupy the clamping-bolt-openings in the clamp-base-plate and said extension-bar; and a screw-bolt-connection between the other end of said complementary clamping-member and the other end of said clamp-base-plate. 100

In testimony whereof, I have hereunto set my hand this 26th day of March 1915.

WALLACE F. WOLFE.
